UNITED STATES PATENT OFFICE.

BESSIE AVRON, OF NEW YORK, N. Y.

COMBINATION UNDERGARMENT.

Application filed October 10, 1927. Serial No. 225,315.

My present invention relates to combination undergarments for ladies and in a preferred specific embodiment to a combination brassière and bloomer.

5 It is among the objects of the invention to provide a combination garment of the above type devoid of elastic widths, panels or gussets, which will permit bending or stretching of the wearer without binding, slipping or 10 substantial strain.

According to another object the various advantages of the known modern brassière and of the known modern bloomer are obtained in the combination garment without 15 sacrifice of convenience, the support of the bloomer element being accomplished without undue pressure due to the contraction of elastic against the abdomen.

Another object is to provide a garment of 20 the above type devoid of buckles, clasps, buttons or straps that are apt to produce the appearance of a bulge when worn under thin or sheer dresses.

To enable others skilled in the art to fully 25 comprehend the underlying features of my invention that they may embody the same in the various modifications in structure and relation contemplated, a drawing depicting a preferred form has been annexed as a part 30 of this disclosure and in such drawing, similar reference characters denote corresponding parts throughout all the views, of which,

Figure 1 is a view in front elevation of my improved combination undergarment showing 35 the tucks incorporated in the brassière to shape the same and also the reinforcing strip used in the garment to prevent wrinkling and bulging thereof.

Figure 2 is a view in rear elevation of the 40 garment shown in Figure 1, the same illustrating how the band pieces of the brassière are separated from the bloomers to afford free movement to the wearer, and

Figure 3 is an enlarged section taken on the 45 line 3—3 of Figure 1 showing how the reinforcing strip is secured across the front of the garment to prevent the same from bulging or wrinkling.

Referring to the drawings in detail, 5 indicates generally the garment which consists of an upper or brassière portion 6 which, at its top edge is provided with the hem 7 and suitable shoulder straps 8, through the medium of which the garment is supported on 55 the wearer. The front portion of the brassière is formed integrally with the bloomers

9, the brassière being narrowed down to provide the band pieces 10 at the back of the garment, which are reinforced as at 11 through the medium of the hem to prevent the material from unravelling. The band pieces are releasably secured together through the medium of an elastic connector 12 which is sewn as at 13 to the end of one of the band pieces 10 and carries the eyes 14 which may 60 engage the hooks 15 carried on the edge of the opposite band piece 10.

In order to shape the brassière, the same is provided with body encircling tucks 16 which terminate in the bust portion of the 70 brassière as at 17 and adjacent the upper end of vertically disposed tucks 18, said tucks cooperating to shape the brassière portion and give it the proper fit. The upper edge of the rear portion of the bloomers is provided with a fluting 19 in which is held a suitable elastic member so that the bloomers at the rear of the waist of the wearer fit comfortably and yieldably, it being unnecessary 75 to illustrate the elastic band as the use of 80 such a member is well known for the purpose described. This elastic band is terminated at the end of the fluting and the fluting itself terminates at the point of connection of the brassière portion of the garment and the 85 front of the bloomers. Extending across this portion referred to, I have provided a reinforcing strip 20 which is securely sewed as at 21 and is widest in its mid portion 22 so that the garment is not only reinforced at 90 the waist portion but the piece of reinforcing cloth prevents wrinkling at the front of the garment and consequent bulging which is unsightly and spoils the contour of the light 95 outer garments as worn thereover.

In order to provide the necessary fullness at the sides of the bloomer, I have provided the darts 23 which are caught under the reinforcing strip and suitably sewn as indicated. The lower side edges of the legs of the 100 bloomer 9 are slit as at 24 and thus provide a leg opening. The bottom of the bloomer legs are fluted as at 25 and gathered to encase an elastic member which is sewn therein and which allows the legs of the bloomer to 105 be snugly fitted about the legs of the wearer, the legs of the bloomer being closed through the medium of suitable ribbon 26 or other suitable tying means.

In order to provide the roominess desirable 110 in garments of this character, I have provided an insert 27 at the rear of the garment

which begins at a point adjacent the waist as at 28 and terminates in the crotch portion 29 of the bloomer, the bloomer construction being completed by the sewing 30 at either 5 end of the insert 27, as illustrated.

It will be quite evident, therefore, that I have provided a combination undergarment which not only allows full freedom during the bending and other movements of the 10 wearer but also one in which a brassière and bloomer is made as an integral unit, the brassière being suitably sewn to give it shape to snugly fit the body of the wearer and the bloomer portion being reinforced to provide 15 at its front a smooth surface so that outer garments will not bulge or show any unevenness in the undergarment which has heretofore been so objectionable.

It is also evident that I have provided in a 20 combination undergarment a pair of bloomers which are roomy and which are so constructed that they will snugly fit the wearer and may be adjusted in the leg size for comfort.

25 In effect the front 6 of the brassière and the front 9 (Fig. 1) of the bloomer constitute a substantially continuous front panel portion covering the bust and the legs, while the rear or seat section 9 (Fig. 2) is retained at 30 its lateral edges to the outer edges of the leg portion. The term "retained" as here used and as used in the claims is intended generally to embrace an integral or unitary relation of parts or a connection by seam or 35 equivalent means.

While I have illustrated and described my invention with some degree of particularity, I realize that in practice various alterations therein may be made. I therefore reserve the

right and privilege of changing the form of 40 the details of construction or otherwise altering the arrangement of the correlated parts without departing from the spirit of the invention or the scope of the appended claims.

Having thus described my invention, what 45 I claim as new and desire to secure by United States Letters Patent is:—

1. A lady's combination undergarment comprising a substantially continuous inelastic front panel portion covering the bust and the legs, means unitary with the bust portion for retaining the latter about the body, shoulder straps connecting the top of said bust portion to said means, a seat section permanently retained at the lateral edges of the leg 50 portion, said seat section having an elastic waist strip along the entire length thereof permanently secured at its ends to the sides of the front portion and constituting the sole means for retaining the seat portion in elevated position.

2. A lady's combination undergarment comprising a brassière portion of the type having a pair of band pieces detachably connected at the rear and a pair of shoulder 65 straps, a bloomer portion having the front section thereof rigidly connected to the lower part of the brassière and substantially unitary therewith, having the rear portion thereof permanently retained at its lateral edges 70 at the sides of the front section thereof and including an elastic rear waist band portion permanently secured at its ends to the lateral edges of the front section, one of the legs of the bloomer portion affording access from the 75 lower end thereof.

In testimony whereof I affix my signature.
BESSIE AVRON. [L. S.]
